UNITED STATES PATENT OFFICE.

PHILIPP MÜLLER, OF LEIPZIG, GERMANY, ASSIGNOR, BY MESNE ASSIGNMENTS, TO THE CHEMICAL FOUNDATION, INC., A CORPORATION OF DELAWARE.

APPARATUS FOR EVAPORATING LIQUIDS.

1,406,997.

Specification of Letters Patent. Patented Feb. 21, 1922.

Original application filed August 26, 1913, Serial No. 786,773. Divided and this application filed December 7, 1914. Serial No. 876,001.

To all whom it may concern:

Be it known that I, PHILIPP MÜLLER, merchant, residing at Leipzig, in the Kingdom of Saxony, Germany, have invented, 5 certain new and useful Improvements in Apparatus for Evaporating Liquids, of which the following is a specification.

The invention relates to improvements in apparatus for drying liquids containing 10 solids, damp substances, and the like, and has for its object to enable the drying of the solids of such substances to be effected economically, easily, and rapidly without the employment of high temperatures. This 15 application is a division of my application filed August 26, 1913, Serial Number 786,773, now Patent No. 1,364,403 of Jan. 4, 1921.

In carrying out my invention I project the liquid to be treated, milk for example, 20 continuously into a chamber or passage in a finely sprayed condition in such manner that the stream of finely-divided material forms a flat layer of mist between two layers of a suitable drying agent (for instance air) moved continuously through the chamber closely above and below parallel to and in the same direction as the said layer of finely-divided material so that the individual fine particles of the substance to be dried 25 remain during the whole path in which they are projected in free suspension surrounded by the drying agent and the solids of these particles are rapidly dried at ordinary temperature.

30 In the accompanying drawings are illustrated several typical forms of apparatus for carrying out the invention.

Fig. 1 shows a central longitudinal section of the preferred form of apparatus;

40 Figures 2 to 6 are detail views from parts of the apparatus;

Figure 7 is a central longitudinal section of a modified form of the apparatus and

45 Figure 8 is a central longitudinal section of another modified form of the apparatus.

In these drawings corresponding parts of apparatus are marked with the same reference numerals.

50 Referring to the drawings 1 is a drying chamber closed on all sides; 2 is a receptacle for the liquid which is to be dried in the

chamber 1; 3 is a wall down which the liquid is allowed to trickle, said wall, which is preferably arranged in a known manner as an attemperator, communicating at the top with the receptacle 2 or other feed device which contains the supply of liquid. The wall 3 is preferably corrugated on the surface, but may also be smooth and arranged to slope at any desired angle, or 60 may even be vertical. On this wall 3 is provided a pipe 4 having a series of fine perforations 5 or a slit. Fig. 2 illustrates the perforated modification. The pipe 4 may also be mounted separately behind the 65 wall, in which case its openings correspond with openings in the wall 3. Opposite the openings is a slit 6 arranged in the upper part of the drying chamber 1. 7 represents feed pipes for the drying agent (air or the 70 like), these feed pipes being arranged parallel to the slit 6 of the drying chamber 1 near the wall within the chamber closely above and below the slit 6 and these feed pipes are provided with nozzles which may converge 75 toward the atomized current of liquid issuing from the wall 3. 8 is a belt conveyor, carried over rollers 9, for removing the dried particles of the liquid from the drying chamber 1. 10 is a scraper for removing the 80 dried particles of liquid from the belt conveyor 8, and 11 is a receptacle for collecting the dried particles of liquid removed by the scraper 10. 12 are exhaust flues for withdrawing the drying agents laden with 85 moisture.

The apparatus operates as follows:

The liquid to be dried, supplied in regulated quantity from the vessel 2 to the wall 3, is discharged by means of a suitable atomizing 90 medium, compressed air for example, through the slit 6 into the drying chamber 1 in a very finely-divided state, and in that condition is encountered by the drying agent, entering from the parallel rows of 95 pipes 7 above and below the slit 6 of the chamber 1, whereupon the drying and precipitation of the solid constituents of the liquid ensue immediately, said constituents subsiding on to the belt conveyor 8 and being removed from the drying chamber 1, whilst the drying agent laden with the mois- 100

ture of the atomized liquid, is withdrawn from the drying chamber through the exhaust flues 12.

The feed pipe for the air or other pressure-medium may also be of the form shown in section in Figure 3, in which a plate 13 is soldered firmly behind one of the corrugations of the wall and the feed pipe receives the pressure-medium from a receptacle not shown by a feed pipe 14.

If it be desired to keep the liquid to be dried out of contact with the surface of the pressure-medium pipe 4 while trickling down the wall 3, the wall may preferably be detached from the pipe 4 and the liquid to be dried is led by means of a guide-plate 15, Figure 4, directly on to the issuing pressure-medium. The space between the guide-plate 15 and the pressure-medium pipe 4 may be reduced or increased in order to secure the most efficient area. Also, as shown in Figure 5, the liquid to be dried can be allowed to drop freely on to the current of pressure-medium.

Again, as shown in Figure 6, the wall 3' may also consist of two sheet metal walls arranged parallel and close together. These walls may also be corrugated, and preferably form a closed pipe 16 or chest at their lower end. In this case the pipe 16 is provided, at the side facing the drying chamber 1, with a series of perforations 17 opposite to which a corresponding number of nozzles, leading from the common pressure-medium vessel, debouch into the pipe 16. The surplus liquid and pressure-medium may be led from the pipe 16 through the two lateral ends thereof.

In this modification of the wall, the liquid is supplied to the atomizing point by being allowed to flow down between the two walls (which may be arranged externally to serve as heaters or coolers), and by being encountered in the pipe 16 by the pressure-medium and projected through the perforations 17 and slit 6 into the drying chamber 1.

The liquid which is to be atomized may be treated beforehand in any desired way; for instance, it may be sterilized, or enriched with any desired substances. Moreover, the pressure-medium current which effects the atomization, may effect the cooling or warming of the liquid to be conveyed or atomized.

The air current itself, which, as already mentioned, may be replaced by another pressure-medium, may be cooled, warmed, purified, dried, moistened or saturated with any desired substances for the purpose of producing special effects. Thus, the sterilizing of milk may be effected by ultra-violet rays. For this purpose a source of light 18, Figure 3, emitting ultra-violet rays, may be mounted for example in front of the wall 3 and above the delivery openings, the rays acting not merely on the finely atomized and aerated

liquid, but also on the liquid which is still trickling down the wall, so that a thoroughly germ-free product is obtained.

An interchange of different liquids under treatment may be effected by placing the wall, down which the liquid flows, in communication with different feed and storage vessels, and allowing the one or the other liquid to flow down the wall as desired.

In the modified construction of drying apparatus shown in Figure 7, 19 is a pipe, preferably controlled by a tap, leading the liquid, which is to be dried, from the receptacle 2, containing the supply of liquid to the drying chamber 1. 20 represents a row of nozzles within the drying chamber 1 to which the liquid to be dried is supplied through pipe 19. 21 is a pipe connecting the row of nozzles 20 with the receptacle 22 for the atomizing medium, compressed air for example. 7 are the feed-pipes for the drying agent (air or the like) arranged closely above and below the row of nozzles 20 within the drying chamber 1.

The mode of operation of this modified construction of apparatus is as follows:—

The liquid to be dried is discharged through the row of nozzles 20 directly into the drying chamber 1 in form of a very finely-divided layer of mist and in that condition is, along the whole path in which it is projected, encountered by the two layers of drying agent resulting from the nozzles of the feed-pipes 7, arranged closely above and below the row of nozzles 20.

Hence, also in this modification of apparatus, during the whole of the drying operation the individual fine particles of the liquid to be dried remain in free suspension, surrounded by the drying agent to which they part with their moisture easily and rapidly so that the drying operation may quickly be accomplished and this at an unusually low temperature.

In the further modification of drying apparatus shown in Figure 8, the device for atomizing the liquid to be dried is arranged in the centre of this chamber. This device consists of an atomizing plate 23, which is driven through the medium of a shaft 24 by means, for instance, of a direct-coupled turbine 25.

The operation of this modification of apparatus is as follows:

The liquid to be dried is introduced into the atomizing plate 23 from the vessel 2 through the pipe 4' under the control of a tap, and by the rapid rotation of the plate (about 12000 revolutions per minute) is dispersed through the chamber 1 as a fine mist. The drying agent is preferably blown radially against the plane of the atomized liquid, from the drying-agent feed pipes 7' situated closely above and beneath said plane. The conveyor 8' arranged under

neath the atomizing plate, consists of a collecting plate driven by the turbine 25, from which plate the dried particles are conducted by a scraper into the receptacle 11 outside the drying chamber 1.

What I claim as my invention and desire to secure by Letters Patent, is:—

1. An apparatus for treating liquids, which comprises a drying chamber provided with a feed opening, a feed wall located outside of said chamber and means for propelling the substance, in finely divided condition, from said wall into said chamber.

2. An apparatus for drying liquids which comprises a drying chamber provided with a feed opening, a feed wall located outside of said chamber, means for propelling the

substance to be dried in finely divided condition from said wall into said chamber, and means for bringing a drying medium into contact with said substance.

3. An apparatus for treating liquids, comprising a drying chamber, a feed wall, a pressure medium pipe and a guide plate located between said wall and said pipe, whereby the substance to be treated is fed to a stream of pressure medium.

In testimony whereof I affix my signature in presence of two witnesses.

PHILIPP MÜLLER.
